UNITED STATES PATENT OFFICE.

FRANKLIN DICKEY, OF OAK PARK, ILLINOIS.

BUILDING-TILE AND WALL.

1,241,350.

Specification of Letters Patent. Patented Sept. 25, 1917.

Application filed February 21, 1916. Serial No. 79,691.

To all whom it may concern:

Be it known that I, FRANKLIN DICKEY, a citizen of the United States, residing at Oak Park, in the county of Cook and State of Illinois, have invented new and useful Improvements in Building-Tiles and Walls, of which the following is a specification.

My invention relates to building-tile and to walls constructed therefrom, and more particularly to hollow building-tile formed preferably of burnt clay, and to walls constructed thereof, and has for its objects: (1) to provide a hollow building-tile, that, when securely mortared together in a completed wall, will furnish voyage for the free passage of air, yet have apertures sufficiently small to prevent the passage of birds, rodents, and the like, therethrough; and (2) to provide a wall constructed of these and related hollow building-tile, and reinforced adequately to withstand both lateral and vertical pressure thereon. These objects I accomplish in the manner and by the means hereinafter described, reference being had to the accompanying drawings, in which—

Figure 1 is a perspective view of my regular apertured tile, to be used as shown in Fig. 7.

Figs. 2 and 3 are perspective views of my special apertured tile, to be used, either singly or in combination, in gable construction, as shown in Fig. 7.

Figs. 4 and 5 are perspective views of the corner and pilaster tile, to be used as shown in Figs. 6 and 7.

Fig. 6 is an angled perspective, showing the corner tile, Fig. 5, in combination with the regular apertured tile in a wall the thickness of which is more than one-half and less than the total width of the abutting regular apertured tile.

Fig. 7 is an angled perspective, showing a section of the completed reinforced wall, with a portion of one course of tile broken away to expose the reinforcing.

To form the straight, or regular, portions of the wall, the tile shown as Figs. 1 and 4 are employed as shown in Fig. 7, the mortar being in both the head joints and the bed joints being anchored by the scorings 2 in Figs. 1, 2 and 3. The two-way tile shown as Fig. 4

I use as pilasters, within and preferably flush with the inner and the outer surfaces of the wall and at such intervals as may be necessary, shifting said tile alternately, so

that, while maintaining the regular bond of the wall I also, by employing two-way tile, provide one continuous way, 3 in Fig. 7, perpendicularly therethrough, to carry the vertical reinforcing in mortar, or concrete, and increase the bearing strength of the wall. To provide against lateral pressure, reinforcing 5 in Fig. 7 is also laid in the mortar of the bed joints, the same running inside the vertical reinforcing 6 in Fig. 7. Lateral pressure is further provided against by the rod, or tube, 7 in Fig. 7, suitable sections of the ends of which are bent at right angles to the main portion and pressed downward into plastic mortar, or concrete, at the top of each of two opposite pilasters, the body of the rod, or tube, extending crosswise from wall to wall between said pilasters.

To form the angular, or corner, portions of the wall, either the tile shown as Fig. 4, or that shown as Fig. 5, is employed. In a wall where the length of the regular apertured tile abutting is one-half its width, the two-way tile shown as Fig. 4, equal in dimensions to the regular apertured tile, are employed as shown in Fig. 7, being crossed alternately to form the corner bond, as shown in said figure, thus also providing one continuous way, 4 in Fig. 7, perpendicularly through the wall at the corner, to carry the vertical reinforcing in mortar, or concrete, and increase the bearing strength of the wall. In a wall where the length of the abutting regular apertured tile is more than one-half and less than its total width, the tile shown as Fig. 5 is employed as shown in Fig. 6, being reversely angled in alternate courses, thus forming the corner bond and providing one continuous way, as and for the purpose set forth relative to the corner tile in Fig. 7 just described, the surface *aa* in Fig. 5 being equal to the length of the abutting regular apertured tile, and the surface *ab* in said figure being equal to one-half the width of the abutting regular apertured tile, so that the joints on the outside surface will break evenly, a suitable section of the longitudinal reinforcing 5 in Fig. 6 being bent at right angles to the main portion thereof, and pressed downward into the plastic mortar, or concrete, as shown in said figure.

To form the gable portions of the wall, 110 the tile shown as Figs. 1, 2 and 3 are employed as shown in Fig. 7. By employing

the special units shown as Figs. 2 and 3 I avoid the loss of time which would result if the corners of the regular apertured tile were to be cut away to the pitch of the roof, 5 besides providing an even surface to which a plate or rafter may be attached. By employing these special units I also prevent, at this point of construction, the leaving of too large apertures, and avoid the necessity 10 of using a wide flange board which would materially decrease the ventilating surface of the gables.

Since my tile are designed primarily for structures such as corn cribs, where it is desirable to have free passage of air through the walls, yet protection against the contents thereof being gnawed, eaten, carried away, or otherwise molested, it will be understood 15 that the apertures in the tile shown as Figs. 1, 2 and 3 are small enough to prevent the passage of birds, rodents, and the like, therethrough, and that an arrangement of the webs in a hollow building-tile to provide 20 this effect is the prime object of my invention. While I show these apertures mainly rectangular, as being, for mechanical reasons, the most likely form, I do not limit myself to this form. Neither do I limit myself to cutting the ends of the tile at right 25 angles, as shown in Figs. 1, 2 and 3, as it might be desirable to cut them slightly oblique, for use in some types of buildings. In general, I am aware that alterations and 30 modifications of the form of the tile as shown in Figs. 1, 2, 3, 4 and 5, and of the method of reinforcing as shown in Figs. 6 and 7, are possible without departing from the scope of my invention, and I do not desire to limit myself to the exact forms or 35

methods shown and described. Also, I dis- 40 claim any invention as to the tile shown as Figs. 4 and 5, except their use in combination with those shown as Figs. 1, 2 and 3 in a wall as herein shown, described and claimed. 45

Having thus described my invention, what I claim as new, and desire to secure by Letters Patent, is—

1. A building tile adapted for use in erecting the walls of corn-cribs and other structures wherein ventilating passages through such walls are essential and to be laid in level courses in building such walls and to constitute a complete section of a course thereof, consisting of a rectangular tile having the depth and thickness required to form the thickness of the wall to be erected, and provided with a comparatively large number of narrow ventilating apertures therethrough, whereby the entrance of weather and rodents is effectually prevented. 55

2. A wall for corn-cribs and other structures comprised of rectangular tiles laid in level courses and each constituting a complete section of a course thereof, each of said 60 tiles being of a substantial depth and of a thickness to form the wall, and provided with a comparatively large number of narrow ventilating apertures therethrough, whereby the entrance of weather and rodents is effectually prevented. 70

In testimony whereof I have hereunto set my hand in the presence of two subscribing witnesses.

FRANKLIN DICKEY.
